UNITED STATES PATENT OFFICE.

MAX JAKOBSON, OF NEW YORK, N. Y.

SAFETY-COCK FOR GAS-BURNERS.

No. 919,019

Specification of Letters Patent.

Patented April 20, 1909.

Application filed June 24, 1908. Serial No. 440,085.

To all whom it may concern:

Be it known that I, MAX JAKOBSON, a citizen of the United States of America, residing at New York, in the borough of Manhattan, county and State of New York, have invented certain new and useful Improvements in Safety-Cocks for Gas-Burners, of which the following is a specification.

This invention relates to certain improvements in the safety gas-cock for which Letters Patent were granted to me on October 29, 1901, No. 685,612.

It was found by practical tests that the safety gas-cock referred to was not simple enough for being produced at a low price nor effective enough for practical use, for the reason that the spring-actuated locking pin by which the plug was locked in position, and which was operated by a pivoted lever when turning the plug, was not reliable enough in operation.

The object of this invention is to improve the safety gas-cock referred to and make it in such a manner that the same is locked in a reliable manner when the plug is closed so as to prevent the accidental opening of the same and the dangerous escape of gas, while it permits the easy and reliable operation of the gas-cock when opening and closing the same; and for this purpose the invention consists in the novel construction to be hereafter described and claimed.

In the accompanying drawings, Figure 1 represents a side-elevation of a gas-fixture or bracket with my improved safety-gas-cock, Fig. 2 is a longitudinal section through the same, drawn on a larger scale, and Fig. 3 is a longitudinal section on line 3, 3, Fig. 2.

Similar letters of reference indicate corresponding parts.

Referring to the drawings, A represents a suitable gas-fixture or bracket provided with the usual burner or with a nipple for applying a gas-hose. Turning within the bearing-sleeve *a* of the gas-fixture A is arranged the usual rotary plug *C* of the gas-cock, which plug is provided with an operating key or handle *C*¹ and with a transverse passage *C*² through which the gas may pass to the burner when the gas-cock is placed in open position. To the plug *C* is pivoted by means of a pin *d* a small finger-lever *D* so that its one end extends into a recess or notch *d*¹ in the stock of the gas-fixture or bracket, while the other end is formed in the shape of a handle and located near the handle *C*¹ of

the plug *C* so as to permit the handle-end of the lever *D* to be depressed when taking hold of the handle *C*¹ and turning the plug for admitting gas to the burner. The fulcrumed finger-lever *D* is acted on by a helical spring *e*, which is arranged below the pivot in a socket *e*¹ in the turning handle of the gas-cock. The notch *d*¹ is formed at the edge of the lower open end of the bearing-sleeve *a*, and directly below said notch the fulcrumed lever *D* is pivoted by means of its transverse pin *d*. Immediately below the pivot *d* the socket *e*¹ is formed in the plug, and this socket holds the helical spring *e* which extends at one end over a projection *d*² formed integral with the lever *D* at its inner edge below the pivot. At its lower part the lever *D* is bent at right angles to the upper portion of the same, so as to form a thumb-piece, which extends alongside the key or handle of the plug, parallel to the latter.

The upper end of the plug is seated in the socket or stock of the gas-fixture or bracket and tightly held therein by means of a washer *f*, screw-nut *f*¹ and jam-nut *f*² so that the proper degree of friction is exerted on the gas-cock so as to permit the tight fitting and closing of the same, as shown in Fig. 1. The rim of the stock or socket for the plug is provided at one side, adjacent to the screw-socket by which the gas-fixture or bracket is attached to the service-pipe, with a recess against which a pin *p*, that is screwed into the shank of the plug, abuts in opening or closing the cock in the usual manner. At the opposite side of the stock of the gas-fixture is arranged the notch or recess *d*¹ into which the end of the finger-lever projects when the plug is in closed position so as to prevent the passage of the gas and hold the plug in locked position so as to prevent the accidental opening of the same and escape of gas through the gas-fixture or bracket.

By taking hold of the handle of the plug with the finger and the handle-end of the finger-lever by the thumb and pressing the handles together, the lever is released from the notch or recess *d*¹ in the stock or socket of the gas-fixture so as to permit the turning of the plug and the placing of the same in open position, with the handles in line with the longitudinal axis of the gas-fixture or bracket, as customary when opening a gas-cock. When the plug is in open position the end of the finger-lever rests on the rim

2
of the stock or socket of the gas-fixture or bracket, ready for returning the end of the finger-lever into the notch d^1 when the gas-cock is turned in closed position. When 5 closing the gas-cock the finger-lever automatically engages with the notch or recess d^1 in the plug and prevents the accidental opening of the cock and escape of gas through the same.

10 Having thus described my invention, I claim as new and desire to secure by Letters Patent:

The combination with a gas-fixture or bracket having a bearing-sleeve open at its 15 lower end and provided at its lower edge with a notch, of a plug turning in said bearing-sleeve and provided with a key or handle and a socket cut laterally in the plug above said handle, a transverse pivot- 20 pin mounted in the plug immediately above

said socket, a lever fulcrumed intermediate of its length on said pivot pin and bent intermediately to form two portions which extend at right angles to each other, the upper portion extending into said notch of 25 the bearing-sleeve and the lower portion extending alongside and parallel with the plug-handle, a projection formed on said lever at its inner edge opposite said socket immediately below the pivot pin, and a 30 helical spring seated in said socket and fitting over said projection.

In testimony, that I claim the foregoing as my invention, I have signed my name in presence of two subscribing witnesses.

MAX JAKOBSON.
